UNITED STATES PATENT OFFICE.

ISAAC J. D. FAIRHURST, OF COBB, WISCONSIN.

DESIGN FOR A COCKEYE.

SPECIFICATION forming part of Design No. 34,070, dated February 12, 1901.

Application filed January 17, 1901. Serial No. 43,671. Term of patent 14 years.

To all whom it may concern:

Be it known that I, ISAAC J. D. FAIRHURST, a citizen of the United States, residing at Cobb, in the county of Iowa and State of Wisconsin, have invented and produced a certain new and original Design for Cockeyes; and I do declare the following to be a full, clear, and exact description of the invention, such as will enable others skilled in the art to which it appertains to make and use the same.

The invention relates to a new and original design for cockeyes; and it consists of a design of the configuration shown in the accompanying drawing, in which I have represented my invention in plan view.

The leading feature of the design comprises a loop 1, contracted at 2 and from which pro-

jects a cylindrical extension 3, having a rectangular bail 4. A narrow strip 5 projects downwardly from the neck within the loop and extends to a point within the loop below its contracted portion and ends at a distance above the lower wall of the loop.

What I claim is—

The design for a cockeye as herein shown and described.

In testimony whereof I have hereunto set my hand in presence of two subscribing witnesses.

ISAAC J. D. FAIRHURST.
